[57] CLAIM

The ornamental design for a central processing unit for
electronic filing system, as shown and described.

DESCRIPTION

FIG. 1 is a front elevational view of the central processing
unit for electronic filing system showing my new
design;

FIG. 2 is a rear elevational view thereof;

FIG. 3 is a top plan view thereof;

FIG. 4 is a bottom plan view thereof;

FIG. 5 is a right side elevational view, the left side
elevational view being a mirror image thereof; and
FIG. 6 is a top, front, right side perspective view
thereof on an enlarged scale.
